UNITED STATES PATENT OFFICE.

JAMES HOBBS, OF BELLAIRE, OHIO, ASSIGNOR TO HIMSELF AND BELMONT
GLASS-WORKS, OF SAME PLACE.

DESIGN FOR GOBLETS, &c.

Specification forming part of Design No. **6,976**, dated November 4, 1873; application filed October 6, 1873.
[Term of Patent 3½ years.]

To all whom it may concern:

Be it known that I, JAMES HOBBS, of Bellaire, in the county of Belmont and State of Ohio, have invented a new and useful Design for Goblets, &c.; and I do hereby declare the following to be a full, clear, and exact description of the same, reference being had to the accompanying drawing forming a part of this specification, in which the figure is an elevation.

The invention relates to a peculiar configuration of the outside of a drinking-goblet, whereby is produced a new design, which presents an attractive aspect and produces a pleasing effect upon the beholder.

A is the bowl, made perfectly plain on its outer surface, provided with the curved bulge

a at the bottom, and resting on the distinct bottom plate B. C is the stem, also entirely plain, having the head *c* connected by the intermediate pillar *c'* with the foot *c''*, that rests upon the base D. The entirety is thus made to exhibit a chaste and unique appearance, presenting no salient features of construction to distract the eye, but having its parts composed of graceful curves, all blending into a common unit.

What I claim is—

The design for goblets, as shown and described.

JAMES HOBBS.
